UNITED STATES PATENT OFFICE.

GRANT SIPP, OF PATERSON, NEW JERSEY.

WARPING AND BEAMING MACHINE.

1,262,858.

Specification of Letters Patent. Patented Apr. 16, 1918.

Application filed March 9, 1917. Serial No. 153,562.

To all whom it may concern:

Be it known that I, GRANT SIPP, a citizen of the United States, residing at Paterson, in the county of Passaic and State of New Jersey, have invented certain new and useful Improvements in Warping and Beaming Machines, of which the following is a specification.

This invention consists in improvements 10 in machines for warping and beaming, the same having for their objects, first, so to construct a carriage structure for such machines with relation to the usual pair of rods or other ways on which it travels as to reduce to the minimum both friction and lost 15 motion, thus to obtain a free and perfectly rectilinear movement of the carriage structure and more accurate disposition of the warp; second, to provide a certain novel 20 adjustment of the reed in the reed or warping carriage; third, to provide means whereby to facilitate the control of a warping machine reel, and, fourth, to provide a means whereby, in section warping, the attendant 25 can with increased facility accurately gage the resetting positions of the warping carriage.

In the accompanying drawings,

Figure 1 is a side elevation of the warping 30 means, embodying my improvements, of a machine of the kind indicated;

Fig. 2 is a plan view of the warping carriage, the gage, a part of the means concerned in the control of the reel, and the 35 means for supporting and causing traverse of the carriage;

Fig. 3 is a rear elevation of the carriage and said means;

Fig. 4 is a sectional view on the line 4—4 40 of Fig. 2;

Fig. 5 is an end elevation of the gage;

Fig. 6 shows a side elevation, as seen from the inside of the frame in Fig. 1, of the means for controlling the reel;

Fig. 7 is a plan view of said means; and,

Fig. 8 is a vertical sectional view thereof.

a is the frame of the machine, *b* the reel, and *c* a suitable brake engaging the brake-band *d* of the reel. According to a well-known construction, the reel is driven by the peripheral contact of friction wheel *e* with the band *d* of the reel, the friction wheel *e* and a cone pulley *f* being fast on a shaft *g* which is journaled in a fulcrumed

arm *h*. The parts *e*, *f*, *g*, during warping, 55 are kept continuously in rotation, as by a belt extending around the pulley *f* and driven from some suitable shaft (not shown). The usual lever *i*, for shifting the wheel *e*, engages at one end under the shaft 60 *g*, and at the other end is connected with a foot treadle *j* by a turn buckle *k*, the treadle being normally elevated by a spring *l*. When the operator presses on the treadle, the rotating friction wheel is moved against 65 the reel band *d*, so that the reel is driven against the resistance of the brake, the pressure being removed from the treadle and the friction wheel falling out of contact with the band *d*, the brake brings the reel im- 70 mediately to a stop.

There is the usual pair of parallel stationary shafts *m* affording ways on which travels, parallel with the reel axis, the warping carriage *n*, its traverse being effected 75 from a rotary screw *o* journaled in the frame between the shafts *m* and having a sprocket-and-chain connection *p* with the shaft of the reel *b*.

The carriage *n* is equipped on the under 80 side with a bracket structure *q* cored to receive the rear shaft *m*, and in each end thereof are journaled four rollers *r* engaging the top, bottom, front and rear sides of said rear shaft. Forward of the two-point 85 anti-friction bearing means thus afforded there is arranged in the carriage another roller *s* which runs on the top of the front shaft *m*. The rollers *r* and *s* permit the carriage to travel substantially without friction along its ways, while the two sets of rollers *r* also serve to hold the carriage from any lost motion whatever—an item of great 90 importance in warping, since the slightest unintended movement of the carriage other 95 than perfect rectilinear movement is likely to lead to serious defects in the warp, as by overlapping or undue spacing of the threads, in laying it on the reel; further, the construction is such that the carriage can, if 100 necessary in effecting repairs, be elevated on the rear shaft *m* as a fulcrum, having first removed the screw *o*.

For the adjustment of the reed *t*, toward and from the reel said reed is mounted in a 105 bracket *u* arranged to slide on the elevated longitudinally slotted portion of a bar *v* bolted to the top of the carriage in perpen-

dicular relation to the reel, said bracket being equipped with suitable means *w* for clamping it to the bar.

The warp carriage is disconnectively connected with the screw *o* by the worm-wheel *y* arranged on a spindle *z* on which is the hand-nut *2*, the spindle being set in a bracket *3* depending from the carriage and which is abutted on either side by the worm-wheel *10* and nut. When the carriage is to be traversed by the screw the worm-wheel is clamped fast to the carriage by tightening up the nut; in order to render the carriage movable independently of the screw, the nut *15* is loosened, permitting the worm-wheel to turn freely on the spindle *z*.

In section warping, the sections of warp are successively laid on the reel side by side, and due to the traverse each is wound helically on the reel. The start of the winding of each section should begin in such relation to the beginning of the preceding section that their two adjoining lateral threads will be spaced exactly the same as any two threads in either. The gage shown in Figs. 2 and 5 is designed to promote accuracy in re-setting the carriage to the proper starting point following the winding-on of one section and before beginning to wind the next. There is a member *4* formed with a collar *4'* to embrace one shaft *m* and a fork *4''* (penetrated by but not engaged with the threading of screw *o*) to engage the other (Fig. 5), and projecting laterally from it, parallel with said shafts, a rigid rod *5*. There is also a device in the form of a collar *6* slideable on one shaft *m* and penetrated by said rod, and between this collar and member *4* and also penetrated by said rod another member *7*. Members *4* and *7* have set screws *8* and *9*, respectively, to bind them immovably to the shaft *m*; collar *6* has a set screw *10* to secure it in fixed relation to the rod. In the present instance, the carriage traverses from left to right, and is adapted to be re-set from right to left. Before starting the first traverse collar *6* is secured to the rod, and member *4* to the shaft by, adjusting their set screws, collar *6* abutting the carriage (at bracket *3*) and being spaced from member *4* so that with member *7* abutting either member *4* or collar *6* there would be a space between the other of these latter and member *7* equal to the width of each section. After the first traverse of the carriage is completed member *7* is made to abut member *4* and secured by its screw *9* and then, having released screw *8*, member *4* is shifted to the left, carrying with it collar *6*, until the latter abuts member *7*. The carriage is now re-set until it abuts collar *6*, thus covering its traverse distance plus the width of each section and coming in its new position exactly where it should be for properly starting the next sec-

tion. When the second traverse is completed, member *7* is re-set and secured to the shaft in contact with member *4*, then member *4* shifted again to the left until collar *6* abuts member *7*, and finally the carriage moved back into contact with collar *6*, being then in exact position for the winding of the third section. This operation is repeated for gaging the new position of the carriage following each traverse. 75

In order to keep the reel rotating by automatic means for holding the lever depressed and yet provide for facile and quick release of the treadle and prompt stopping of the reel I provide the following mechanism: 80 The free end of the lever *i* plays in a vertical slot of a bracket *11* and is overhung by a lug *12* on the bracket. There is a latch *13* fulcrumed in this bracket on a vertical axis, one end underlying the lug *12* and having a 85 lateral projection *14* formed with an underneath shoulder *15*; the other arm of the latch is connected with a pin *16* projecting from the bracket by a light spring *17* which holds the latch normally in the position shown in Fig. 7, and connected to it is a horizontal operating rod *18* which extends across the machine and may be supported by a hook *19* depending from the warping carriage. If the operator desires to leave the reel in motion 90 without holding his foot on the treadle, he depresses the treadle and by shifting rod *18* to the right swings the end of the latch having the projection *14* into such position that such projection will overlie the (depressed) 100 lever *i*, upwardly abutting the lug *12*. The friction offered by lever *i* and lug *12* will be sufficient to prevent spring *17* from retracting latch *13*. The friction wheel *e* will thus be held against the band *d* of the reel, keeping the latter in rotation. To stop the reel, the operator has only to move rod *18* to the left to clear projection *14* from lever *i* so that spring *l* will cause the free end of lever *i* to be raised and the friction wheel to fall 110 out of contact with the band *d*; or the same result can be accomplished by depressing and immediately releasing the treadle *j*, the spring *17* operating in the interim between depressing and releasing the treadle to retract latch *13* out of detent relation to lever *i*. 115

Having thus fully described my invention, what I claim as new and desire to secure by Letters Patent is:

1. In combination, a warping machine carriage, a reed, an arched bar secured on the carriage longitudinally of the warp, and means, adjustable longitudinally of the bar, for supporting the reed. 120
2. In combination, the frame having a horizontal guideway, a warping carriage movable along the guideway, means to traverse the carriage, and a gage for the resetting of the carriage including two members 125
130

having sliding connection with each other and also shiftable each longitudinally of the guideway and means to secure one member to the frame on each shifting thereof.

3. In combination, the frame having a horizontal guideway, a warping carriage movable along the guideway, means to traverse the carriage, and a gage for the reset-

ting of the carriage including a member 10 shiftable on and having a rod parallel with the guideway, a collar adjustable on the rod, and another member shiftable on the guideway and arranged between and abuttable by said first-named member and the collar.

In testimony whereof I affix my signature.

GRANT SIPP.
